UNITED STATES PATENT OFFICE.

JACOB E. NEAHR, OF HARTSDALE, NEW YORK, ASSIGNOR TO UNDERWOOD TYPEWRITER COMPANY, OF NEW YORK, N. Y., A CORPORATION OF DELAWARE.

DESIGN FOR A TYPEWRITER STAND.

Application filed October 3, 1921. Serial No. 505,193. Term of patent 14 years.

To all whom it may concern:

Be it known that I, JACOB E. NEAHR, a citizen of the United States, residing in Hartsdale, in the county of Westchester and State of New York, have invented a new, original, and ornamental Design for Typewriter Stands, of which the following is a specification, reference being had to the accompanying drawing, forming part thereof.

The figure is a perspective view of a typewriter stand, showing my new design.

I claim:

The ornamental design for a typewriter stand, as shown.

JACOB E. NEAHR.
